CLAIM

The ornamental design for a cane handle, as shown and
described.

DESCRIPTION

FIG. 1 is a right side elevational view of a cane handle
showing my new design, the opposite side being a mirror
image; the broken lines are for illustrative purposes
only;

FIG. 2 is a front elevational view thereof;

FIG. 3 is a rear elevational view thereof;

FIG. 4 is a top plan view thereof; and

FIG. 5 is a bottom plan view thereof.

FIG. 2

FIG. 1

FIG. 3

FIG. 4

FIG. 5
